UNITED STATES PATENT OFFICE

WILLARD P. FOWLER, OF METROPOLIS, ILLINOIS

SIGNALING SYSTEM

Application filed October 13, 1927. Serial No. 225,918.

This invention relates to signaling systems, and especially to an improved automatic railway crossing signal, and is an improvement on the device covered by my Patent Number 1,595,460.

One object of this invention is to provide a railway crossing signal which automatically operates to announce the approach of a car or train on a railway track, to retain one or more 10 signaling elements in the signaling position until the car or train has entirely passed the crossing and the signaling element, then automatically move the signaling element into a position for indicating the fact that the train 15 has passed, or out of the above mentioned signaling position.

A further object of this invention is to provide an improved mechanically operated and electrically controlled device for operating a 20 railway gate or other signaling element so as to move such signaling element from a vertical position to a horizontal position, and vice versa, such electro-mechanical device being entirely automatic; that is, entirely dependent upon the approach and departure of 25 locomotive, car or train, for starting and stopping and reversing the mechanical elements which operate the signaling element.

Another object of the invention is to provide 30 an improved device of this character having all its parts united, except the railway and its electrical connections, or consisting of a unitary combination which is capable of being carried bodily, thereby avoiding the 35 necessity of building the device at the place it is to be installed at a railway crossing.

Another object is to provide an improved device of this character which consists of comparatively few and very strong and durable 40 parts, thus providing the maximum service and efficiency at a comparatively low cost of installing and maintaining the device.

Another object is to provide a device of this character with a battery and a step-down 45 transformer or reducer, and provide these with a switch whereby either may be used to connect the controlling relay with the insulated section of railway track, thereby suiting the device to various conditions, environments and circumstances.

Another object is to greatly simplify and minimize the cost of constructing, installing and maintaining a signaling device of this character, at the same time providing for electrically connecting any desired number 55 of the signal-operating mechanisms to a single dynamo which is preferably located adjacent to the railway track, so an attendant may manage the operation of such dynamo while being convenient to the railway for traveling 60 thereon (on a hand-car or other appropriate means) from one to another of said signal-controlling devices.

Other objects and important features are pointed out or implied in the following details of description, in connection with the 65 accompanying drawings in which:

Fig. 1 is a view mainly in side elevation, but partly in vertical section, and partly diagrammatic, certain parts being broken away 70 for showing other parts, and for lack of sufficient space to show some of the parts in their entirety.

Fig. 2 is a diagrammatic view of the electrical system which operates and controls the 75 mechanism for raising and lowering the pole, paddle or gate which constitutes the signaling element above referred to.

It is generally and well known that a paddle or pole which is extended across a wagon 80 road (this term to distinguish from a railroad) is intended more particularly to warn the drivers of wagons and other vehicles, as well as pedestrians and equestrians, instead of actually making it impossible for them to cross the railroad. Pedestrians often cross 85 in spite of a warning given by the signal. Therefore, the bar or paddle here operated as a gate is, in its broadest sense, a signaling element, and will hereafter be referred to 90 as such. This gate or signaling element is here referred to or designated by the numeral 5, and a sufficient portion of it is here shown to make clear its operation. It is shown in full lines in its horizontal position, and in 95 broken lines in its vertical position. It is clamped or otherwise secured on a stud or stub shaft 6 which is journaled in an upright frame element 7, the latter being secured on a base 8, which latter also supports other up- 100

right frame elements which will presently be described. A shaft 9 is also journaled in the upright frame element 7, and this shaft carries a gear wheel 10 which meshes with a gear wheel 11 on the stub-shaft 6. The shaft 9 also carries a segmental gear 12 which meshes with a worm 13. This worm is secured on a shaft 14 which is journaled in suitable bearings on the upright 7 and on a somewhat similar upright 7^a. Beveled gear wheels 15 and 16 are formed integrally with or united with annular clutch elements 15^a and 16^a. Each of these gear wheels is rotatable with its contiguous clutch element around the shaft 14, being journaled on the latter. A pair of clutch levers 17 is provided for each of the clutch elements 15^a and 16^a, each of these clutch levers 17 being provided with a friction-element 18 and with an adjusting screw 19. A sleeve 20 is feather-keyed or otherwise secured against rotation on the shaft 14, and has inclined ends on which the adjusting screws 19 slide for swinging the lever 17 of each pair so as to bring the friction-elements 18 into frictional engagement with the clutch elements 15^a and 16^a. The middle part of the member 20 is provided with an annular groove 21 in which a stud 22 extends from a lever 23 which is pivoted on an upright 24 and has a slot 23^a in its upper end.

A beveled gear wheel 25 is mounted on a shaft 26 and is continually in mesh with the beveled gear wheels 15 and 16. A worm gear wheel 27 is also secured on the shaft 26 and serves as a driving wheel for the gear wheel 25. This wheel 27 is driven by a worm 28 which has its shaft 29 journaled in suitable bearings on the base 8. The shaft 29 is driven by an electric motor 30 which may be of any appropriate kind or type.

A main actuating bar 31 is provided with a slot 31^a, and a double-headed pin or bolt 32 extends through the slots 23^a and 31^a so as to operatively connect the lever 23 with the bar 31 for a purpose which will hereafter be explained. A link 33 is pivotally connected to the bar 31 and to a supporting element 7^b which is secured on the upright 7^a. A link 34 is also pivotally connected to the bar 31, preferably by the same pivot 31^b which connects the link 33 to the bar 31. A contractile spring 35 has its upper end secured to the link 34, and has its lower end secured to an element 36 on the base 8. This spring holds the bar 31 alternately in the broken line positions 31A and 31B, and also forces this bar to either of said broken line positions when it has passed slightly beyond its neutral position which is shown in full lines; that is, when the link 33 has passed slightly beyond its vertical position, or carried its pivot 31^b beyond the plane which is common to the fixed pivot of the link 33 and the fixed connection of the spring 35. The

bar 31 rests upon the upper end 7^c of the upright 7^a, when said bar is in either of its positions 31A and 31B. It will be seen that when the bar 31 moves rightward to the position 31A, it swings the lever 23 for rendering the clutch levers 17 effective for securing the gear wheel 16 against rotation on the shaft 26; that is, it locks the gear wheel 16 to the shaft 14 so that when the gear 16 turns, it turns the shaft 14 and thereby turns the worm 13 in the direction for turning the segmental gear 12 in the direction of its arrow. An arm 37 is either clamped on a hub of the gear segment 12, or secured to the shaft 9 by any appropriate means, and this arm is connected by a link 38 to a lever 39 which is pivoted at 40 to a bearing secured on an insulated platform 41, the latter being supported by the upright frame element 7. The lower end of the lever 39 is pivotally connected to a link 42, and the latter is pivotally connected to a lever 43 which is pivotally mounted at 44 on the base 8. The letter *a* and the adjacent broken line indicate the plane of the pivots of the lever 43 when near its leftward position of Figure 1, and the letter *A* indicates the plane of such pivots near the extreme rightward position of the lever 43. Similarly the broken line at *b* indicates the plane coinciding with the center of the spring 35 and link 34 when they are near their leftward position, and the broken line *B* indicates the plane coinciding with the centers of the elements 34 and 35 when near their extreme rightward position.

A single pole double throw switch 45 is pivotally mounted at 46 on the insulated platform 41, and this switch includes two contacts 47 and 48. This switch will hereinafter be referred to as the S. P. D. T. switch. Its upper end is provided with a slot 45^a through which a stud 49 extends from an arm 50 which is pivotally connected at 51 on the bar 31. The upper end of the lever 43 is in the path of two spaced abutments 52 and 53 of the bar 31, so that such abutments are engaged by the lever 43 for moving the bar 31 from the positions 31A and 31B to the full line position or slightly past the full line position shown in Figure 1; and when the bar 31 has moved slightly past its full line position, in either direction, the link 34 and spring 35 cooperate in completing the movement of the bar 31 to one or the other of its broken line positions. It will be understood that the lever 43 is moved by the previously described gearing and the system of arms, links and levers 37 to 42 inclusive, and that the space between the abutments 52 and 53 permits the bar 31 to complete its movement to the 31B-position, for instance, while the lever 43 remains near its *a*-position.

It will be understood, from the foregoing, that the S. P. D. T. switch is also operated by the bar 31, this being accomplished

through the medium of the arm or link 50 and its stud 49; and now, it may be well to review the structure thus far described and to explain a cycle of its operation as follows: Assuming that the signaling element has been moved from its upright or broken line position to its horizontal or full line position, by the gearing mechanism previously described, the clutch levers 17 (at the right) being in the effective position shown, so that all parts having arrows thereon are moving in the direction indicated by said arrows, and have so moved until the link 33 has its pivot in the same plane with the spring 35, the connecting stud 32 having just engaged with the right-hand end of the slot 31^a, and the stud 49 having just engaged with the left-hand end of the slot 45^a in the S. P. D. T. switch, the latter being closed with the contact 48 and being open with respect to the contact 47: now, when the gearing continues its movement slightly, for bringing the arm or paddle 5 to the end of its downward movement, such movement of the gearing and system of levers and links moves the bar 31 leftward slightly beyond the full line position, so that the spring 35 and link 34 now quickly shift the bar 31 to the position 31B, and in doing this, the S. P. D. T. switch is opened at 48 and closed at 47. In the operation of thus shifting the S. P. D. T. switch, it is momentarily open at both 47 and 48, which breaks the circuit for a purpose which will presently be explained. Another function of the bar 31, during its quick change from the full-line position 31B, is to shift the lever 23 leftward sufficiently far to move the clutch sleeve 20 out of engagement with the screws 19 of the clutch levers which co-act with the clutch element 16^a, and into engagement with such screws of the clutch levers which co-operate with the clutch element 15^a, thus leaving the bevel gear wheel 16 free to turn on the shaft 14, at the same time locking the bevel gear 15 on the shaft 14, so that when the gear wheel 25 resumes its movement in the direction of its arrow, the shaft 14 will be turned in the direction opposite to that which is indicated by its arrow, and accordingly, the parts 37 and 42, inclusive, swing the lever 43 rightward, and the same, now being against the abutment 53 (clearly shown in my Patent Number 1,595,460), moves the bar 31 rightward until it reaches the full line position here shown. However, it is to be remembered that the S. P. D. T. switch is now in its broken line position, and the lever 23 is in its leftward position, its stud 32 being in the left end of the slot 31^a: and now, when the bar 31 has brought its stud or pivot 31^b slightly to the right of the position here shown, the spring 35 and its link 34 now bring the stud 31^b into the plane indicated by the broken line B. During this reverse movement of the gearing and combi-

nation of links, levers, etc., the paddle or signal element 5 has moved to and slightly beyond the broken line position thereof.

Now, referring to Fig. 2, in which the motor 30 and the S. P. D. T. switch 45—47—48 and adjuncts are the only elements described in the foregoing, I will explain the electrical system which controls the motor 30 and is controlled by the S. P. D. T. switch, as follows:

At 60 is indicated an electrical generator, and it is understood that any form of generator may be employed in connection with the power circuit indicated at 61. A section of railroad track is indicated at 62, insulated (at 62^a) from parts of the track-rails at a distance from the crossing at which this signaling device is installed, that is, at a sufficient distance to permit the arm 5 to be lowered to the horizontal position in consequence of the approach of a car, locomotive or train, before the same arrives at the crossing. In this connection, it should be understood that a pair of wheels and an axle of a truck of such locomotive or car combine to constitute a circuit closer 101, between the rails of the track-section 62. These track-rails are connected with an electro-magnet through the medium of conducting wires 66, 67 and 68, these latter being connected by a battery 69, or by a step-down transformer T, and a switch S. The electro-magnet is indicated at 70, and is secured on a frame or supporting member 71 which may be formed entirely of insulating material or provided with insulating members 72, 73, 74 and 75, the purpose of such insulation being obvious to persons who are acquainted with electric conductors and insulators. An armature-lever 76 is pivoted at 77, on a post 81 which is supported on the member 71 and insulated therefrom by the member 72. A spring 78 constantly tends to pull the contact-end of the member 76 against a stationary contact 79, while the magnet 70 tends to pull said contact-end against a stationary contact 80 when the magnet is energized. The contacts 79, 80 and post 81 are insulated from the body 71 by means of the insulating member 72, and the insulating member 73 insulates the spring 78 from the member 71. The contact 79 extends through the member 71 while being spaced therefrom and connects with a binding post 79^a.

A conducting wire 94 connects the switch-contact 47 with the binding post 79^a. A conducting wire 95 connects one brush or terminal of the generator 60 with a binding post 96 which is secured on and electrically connected to the movable contact or armature 76. The other terminal of the generator 60 is connected to a terminal of the motor 30 by an electric conductor 97, while the other terminal of the motor 30 is connected to the pivot 46 of the S. P. D. T. switch by means of a conductor 98. The switch contact 48 is connected

to the contact 80 by means of a conductor 99.

The operation of the invention is as follows:

When the motor is not energized or in operation and the arm or signaling member 5 is up or in its non-signaling position, or when such arm is beginning to move downward to the signaling position, the S.P.D.T. switch 45 is in closed position with respect to the contact 48 (as shown in Figure 2); but when the member 5 has moved downward sufficiently, so the link 37 effects the movement of the link 33 slightly beyond its vertical position, the spring 35 and link 34 cooperate with the link 33 for quickly shifting the latter leftward, in the direction of the arrow on the member 31, thereby simultaneously shifting the clutch-lever 23 and the S.P.D.T. switch 45, and the circuit between the S.P.D.T. switch and contact 48, so the motor is stopped, and the signaling member 5 remains in the signaling position until the car, locomotive or train passes beyond the track-section 62. When the circuit closer 101 passes beyond the insulated track-section 62, thereby breaking the circuit between the conductors 66 and 67, the battery 69 or transformer T (which is in circuit) is de-energized, the magnet 70 thereby being de-energized, so the spring 78 closes the circuit between the contact members 76 and 79, and this part of the circuit remains closed until the battery 69 or transformer T is again energized by a circuit closer 101 on the track section 62. At this point it will be recalled that the S.P.D.T. switch made contact with the member 47 while the signaling element 5 was being lowered, but the circuit was not then completed until the armature 76 made contact with the member 79; and now, the circuit being completed, and the clutch member 20 being shifted, so the motor 30 is started and causes rotation of the worm 13 in the opposite direction from that in which it turned while lowering the member 5; it will be seen that such member 5 is now raised to its vertical position; but before reaching such vertical position, the arm 37 has effected a rightward movement of the shifting bar 31 to and beyond the full line position shown in Figure 1, so the link 34 and spring 35 cooperate with the link 33 for quickly shifting the bar 31 to its position indicated at 31^a, thereby restoring the clutch and the S.P.D.T. switch to their initial or normal positions, in readiness for again lowering the signaling member 5 (in the manner previously explained), when a circuit-closer 101 again cooperates with the insulated track section for energizing the battery 69 and magnet 70.

It should be understood that the primary coil of the transformer T is in shunt or parallel with the high tension motor circuit, being connected thereto by means of a conducting wire T95 and a second conducting wire 95T.

From the foregoing it will be seen that I

have greatly simplified and reduced the cost of producing and maintaining an automatic signaling system of this character, and while I have described this improvement in detail, it should be understood that my invention is not limited to the exact details of construction and arrangement shown and claimed herein, but changes may be made within the scope of the inventive ideas as implied and claimed. Moreover, it should be understood that while I have shown the generator 60 as operatively connected with only one motor 30 and the means which control the same and are controlled thereby, any appropriate number of such devices or systems can be operated from a single generator which may be stationed in convenient relation with all of the individual signaling systems, by the conductors indicated at 95^a, 97^a, 95^b, 97^b, 95^c, 97^c, 95^d, and 97^d.

What I claim as my invention is:

1. In a railway signaling system, the combination of a signaling member; a reversible gearing operable to move the signaling member to and from its signaling position; a gearing mechanism to drive said reversible gearing; a high tension electric circuit including a motor for driving said gearing mechanism, a double throw switch which includes two contacts and a movable element, the latter being electrically connected to the motor and alternately connectible with said contacts, an electric conductor connected to the other terminal of said motor, means to shift said switch for breaking with one of its contacts and closing with the other one of its contacts, circuit-breaking means automatically operable to break the circuit through the motor upon thus shifting said switch; and an incomplete closing circuit of low tension including a circuit-closing magnet, two railway rails, a step-down transformer, electric conductors connecting said transformer with said magnet and with one of said railway rails, and an electric conductor connecting said magnet with the other one of said railway rails, this incomplete closing circuit being adapted to be completed by a conducting axle and wheels on said railway rails and thus made effective for closing said normally open part of the said high tension circuit, the said transformer including a primary coil in parallel with said high tension circuit.
2. The structure defined by claim 1, a battery having one terminal connected to one terminal of the secondary coil of said step-down transformer, and a switch operable to alternately connect the other terminal of said switch or the other terminal of said secondary coil with one of said track-rails.

In testimony whereof I affix my signature.

WILLARD P. FOWLER.
